United States Patent Office.

JOB SWEET, OF DECATUR, MICHIGAN.

Letters Patent No. 95,393, dated September 28, 1869.

IMPROVED HINGE FOR GATES.

The Schedule referred to in these Letters Patent and making part of the same.

To all whom it may concern:

Be it known that I, JOB SWEET, of Decatur, in the county of Van Buren, and State of Michigan, have invented certain new and useful Improvements in Gate-Hinges; and I do hereby declare that the following is a full, clear, and exact description thereof, reference being had to the accompanying drawings, and to the letters of reference marked thereon, which form a part of this specification, in which the figure in the annexed drawing represents a side elevation of my gate.

The nature of my invention consists in constructing a gate with a hinge formed with an iron rod, the lower end of which is spiral or auger-shaped, and working in a slotted metal plate, and the upper end playing in a strap, as hereinafter set forth.

A represents a gate, constructed in the usual manner.

B B' designate the uprights, connected by bars C. To said bars the slats e e e are nailed.

G G' represent the gate-posts, which are mortised into sill E.

The post G is cut away on its inner surface about two-thirds of its width, leaving the remaining third as a rest for the gate when it is closed.

H represents an iron rod, passing in a vertical position through bars C C, the said rod having its lower end formed spirally, and entering a slot in the metal plate f, which is confined to sill E.

The upper end of H plays in a hole in strap g, the said strap being secured by bolts to post G', and then bent at a right angle to receive the end of rod H.

The advantage of my gate is that it is self-shutting, from the fact that the centre of gravity in the rod H will always be in a line with the centre of the slot in plate F, and will tend to reverse the motion of the spiral end, and close the gate.

Having thus described my invention, What I claim, and desire to secure by Letters Patent, is—

A gate, constructed with a rod-hinge, the lower end of which is made in a spiral form, and operating in a slotted plate, as and for the purpose set forth.

In testimony that I claim the foregoing as my own, I affix my signature, in presence of two witnesses.

JOB SWEET.
